UNITED STATES PATENT OFFICE.

THOMAS HENRY RYAN, OF NEWARK, NEW JERSEY.

SUPPORTING HOOK.

1,406,087.

Specification of Letters Patent. Patented Feb. 7, 1922.

Application filed May 24, 1921. Serial No. 472,034.

To all whom it may concern:

Be it known that I, THOMAS HENRY RYAN, a citizen of the United States, and resident of Newark, in the county of Essex and State of New Jersey, have invented a new and Improved Supporting Hook, of which the following is a full, clear, and exact description.

My invention relates to a supporting hook, and aims to provide a device of this nature that is commonly known as a "pot hook".

As is well known this type of hook is utilized by mechanics, while working upon ladders, and scaffolds, and serves as a supporting element for the receptacle, such as a paint can, whereby both hands of the operator may be free, and the receptacle will at all times be supported in a readily accessible position.

It is understood that mechanics have utilized any available material for forming pot hooks. Aside from the fact that this has wasted the mechanic's time, the members thus provided have been extremely crude and inefficient, in that they have for the most part, supported the receptacle in such a manner that it has been necessary to wire the bail of the same to the hook, and also to use great care in associating the hook with the supporting member from which it was to be suspended.

Thus it is an object of my present invention primarily to provide a supporting hook particularly adapted for use by mechanics and by means of which the bail may readily be attached and detached therefrom so that no delay will be incurred incident to this operation.

A further object of my invention is the construction of a device of the character stated which may readily be attached to the supporting member from which it is to be suspended, and which when in attached position will reduce the liability of its accidentally becoming detached from the supporting member to a minimum.

Still another object of this invention is the provision of a supporting hook which may be manufactured at an extremely nominal figure, thus overcoming any objection upon this point.

Still further objects of my invention will appear in the annexed specification taken in

connection with the drawings, which latter 55 illustrate one practical embodiment of the same, and in which;

Figure 1 is a sectional view of a supporting member such as a ladder, and showing my improved hook supporting a receptacle 60 and being suspended from one of the rungs of the ladder.

Figure 2 is a perspective view of the hook, and

Figure 3 is a sectional side view of the 65 lower portion of the same.

Referring now more particularly to Figure 1 it will be seen that the reference numeral 5 indicates the ladder provided with rungs 6 from which the receptacle 7 is to be 70 suspended by means of my improved type of hook.

This hook preferably includes two major inter-connected portions, one of which permits of an attachment to the supporting 75 member, the second of the same providing a quick detachable element whereby the bail of a receptacle or other element to be supported may readily be associated with or detached from the hook.

With respect to the first major portion it will be seen that the same preferably is composed of a single length of wire, the ends of which are twined about each other so as to provide a portion 8 possessing a relatively 85 great amount of strength. That portion of the wire intermediate its extremities is bent so as to provide a hook 9, the outer end 10 of which is outstruck so as to form a guiding lip to properly guide the hook 9 upon the 90 supporting member, such as the rungs 6 of the ladder 5. The outer ends of the member described are spaced and terminate in loops 11.

The second portion of the supporting hook 95 is also preferably formed by utilizing a single piece of wire, which is bent at a point substantially intermediate its extremities to provide a straight part 12, passing through the loops, and thus affording a swinging 100 suspension for the bail engaging member. At points beyond the loops 11 the body of the latter member is formed with coils 13 providing oppositely acting resilient portions, the outer ends of the wire being bent 105 towards each other, as at 14, and terminating in upturned ends 15 lying against the corresponding portion 14 of the opposite end

of the member, and held in intimate engagement therewith by means of the resilient portions 13 aforescribed.

It will thus be seen that the supporting hook is capable of association with a member in the aforescribed manner, and that the bail 16 of the receptacle 7 may be engaged with that portion of the supporting hook provided for this purpose, by simply slipping the bail between the oppositely pressed ends of the lower part of the supporting hook, and beyond the ends of the same, subsequent to which the bail may be arranged transversely of the body of the receptacle supporting unit and rest within the restricted lower portion 17 thereof.

It will be obvious that in this position no liability of the parts becoming accidentally detached will exist, and that the workmen may readily attach and detach the supporting element from the hook 9 as the occasion demands.

A detachment of the bail 16 from the supporting portion of the hook may be effected by moving the bail upwardly with respect to the ends 15 of this member and in swinging the same to a point at which the bail will lie between the ends 15 and the downwardly extending portions 14 so that the same may freely be slipped out of engagement with the supporting hook, it being noted in this connection that the ends 15 of the lowermost portions of the wire body are preferably formed with undercut lips 18 acting as a guide for and expediting the de-

tachment and attachment of the bail 16 from the supporting hook.

Thus it will be seen that I have provided a device of the character specified by means of which all of the objects set forth in the preamble of this specification will have been accomplished, it being further understood that numerous modifications of structure might readily be resorted to without in the least departing from the spirit of my invention, which I claim as;

A pot hook comprising an attaching member, a supporting member, each member being formed out of a single length of wire, the attaching member being bent upon itself and twined about a point between its extremities to provide the same with a reinforced body portion, the outer extremities of said member being spread apart, and U shaped, the ends of said extremities terminating into a pair of hooks aligned with each other, with their axis of alignment transverse to the longitudinal axis of the twined body portion, said supporting member comprising a body portion held in said hooks, and bent downwardly, a pair of outwardly extending coils having their axis parallel to said axis of alignment, and having its ends extended beyond their intersecting points, which points lie directly below and between said spring coils, said ends being adapted to resiliently separate from each other, in a line transverse to said alignment axis.

THOMAS HENRY RYAN.
